IMPROVEMENT IN BOOT HEELS.

J. H. GREENLEAF, OF NEW HAVEN, CONNECTICUT, ASSIGNOR TO HIMSELF
AND ISAAC N. DANN, OF SAME PLACE.

Letters Patent No. 59,908, dated November 20, 1866.

SPECIFICATION.

TO ALL WHOM IT MAY CONCERN:

Be it known that I, J. H. GREENLEAF, of New Haven, in the county of New Haven, and State of Connecticut, have invented a new Improvement in Heels for Boots and Shoes; and I do hereby declare the following, when taken in connection with the accompanying drawings and the letters of reference marked thereon, to be a full, clear, and exact description of the same, and which said drawings constitute part of this specification, and represent in—

Figure 1, a side view.

Figure 2, a top view.

Figure 3, a bottom view, and in

Figure 4, a vertical section on line $z z$.

My invention relates to the construction of a metallic heel for boots and shoes, and consists in the peculiar construction whereby it is made to receive an India-rubber face for the purpose of giving elasticity to the heel; and that others may be enabled to construct and apply my improvement, I will proceed to describe the same as illustrated in the accompanying drawings.

A is the outer shell or surface of the heel; B an upper plate formed upon the said shell, and provided with holes, a , by which it is secured to the boot or shoe; this upper plate should be made concave to correspond to the form of the sole at that part of the boot. C is a plate fixed within, or made a part of the shell A; at a little distance from the lower edge of the shell, through this plate C, holes d are formed, corresponding to but larger than the holes a ; the shell and two plates are formed from metal cast in the usual manner for casting other articles. Through the holes d , when the heel is placed in its proper position, the requisite nails or equivalent device are inserted into the holes a , to secure the heel to the boot or shoe. That part of the shell below the plate C, is of dovetail form, as seen at f , fig. 4; so that when the heel is secured to the boot or shoe, a piece of India rubber, D, may be inserted into the space below the plate C, and securely held therein, as seen in fig. 4; the rubber should be a little thicker than the depth of the shell to the plate C, that is to say, so that the rubber shall project below the shell, as seen in fig. 4; this gives an elasticity to the heel which gives it a great advantage over ordinary heels. The outer surface of the heel may be finished by japanning or otherwise. I find it in large heels advisable to make the plate C concave upon its under side, so that the rubber will spring into the concavity, and be thereby more securely held in its position. By India rubber, as used for the face of the heel, I mean to be understood as including any of its allied gums or other elastic substances.

I do not broadly claim metallic heels as of my invention; neither do I broadly claim a metallic case for heels when the same is filled with other material, as see the patent of Warner, Hedgins & Travers, July 1, 1840; but what I do claim as new and useful, and desire to secure by Letters Patent, is—

The heel constructed as herein described, that is to say, by the combination of the shell A, the plates B and C, and the elastic face D, substantially as herein set forth.

JOSEPH H. GREENLEAF.
